UNITED STATES PATENT OFFICE.

JAMES HOWELL RAMSDELL, OF NEWTON FALLS, OHIO.

RAIL-JOINT.

1,031,676.

Specification of Letters Patent.

Patented July 2, 1912.

Application filed September 2, 1911. Serial No. 647,460.

To all whom it may concern:

Be it known that I, JAMES H. RAMSDELL, a citizen of the United States, residing at Newton Falls, in the county of Trumbull and State of Ohio, have invented certain new and useful Improvements in Rail-Joints, of which the following is a specification, reference being had to the accompanying drawings.

10 This invention relates to rail joints, and has for its primary object to provide means whereby a very secure connection or joint at the abutting ends of adjacent rail sections is obtained.

15 A further object of the invention resides in the provision of fish-plates adapted to be arranged upon opposite sides of the rails and having flanges extending upon the top and bottom of the base flange of the rail, and interlocking means carried by said flanges to connect the same beneath the rail base.

20 A still further object of the invention is to provide a comparatively simple and effective device of this character which is extremely durable in construction and may be manufactured at a small cost.

25 With the above and other objects in view, the invention consists of the novel features of construction and the combination and arrangement of parts hereinafter fully described and claimed, and illustrated in the accompanying drawings, in which—

30 Figure 1 is a perspective view of my improved rail joint showing the same applied and the rails illustrated in dotted lines; Fig. 2 is a perspective view of one of the rail connecting members or fish-plates; Fig. 3 is an inverted perspective view of the other of said members; Fig. 4 is a transverse section 35 showing the interlocking connection of the fish-plates beneath the rail base; and Fig. 5 is a similar view, illustrating a slightly modified form of the device.

35 Referring in detail to the drawings, R indicates the rail and 5 and 6 designate the fish-plates which constitute the primary elements of my improved joint and are located or arranged upon the opposite faces of the web of the rail and extend upon the adjacent 40 ends of abutting rail sections, as illustrated in Fig. 1. The fish-plate 5 is provided with a laterally extending longitudinal flange a at its lower edge which is downwardly inclined and rests upon the upper surface of the rail base, contacting closely therewith.

45 At the outer edge of this flange a the in-

wardly extending horizontal plate e is formed, the upper surface of said plate being spaced from the under side of the flange a to provide a longitudinally extending recess or chamber in which the base flange of the rail is received. As will be observed upon reference to Fig. 4 of the drawing, the inner edge of this horizontally disposed plate e is located directly beneath the transverse center of the rail, and said plate is of appreciably less thickness than the flange a. This plate has formed upon its under surface a plurality of rectangular lugs or bosses g which are arranged at intervals in spaced relation, as shown in Fig. 3, and are adapted to be received in the similarly shaped recesses or seats f which are provided in the upper surface of the reduced edge portion or flange F which projects from the inner edge of the horizontally extending plate d formed upon the outer edge of the flange b of the fish-plate or joint section 6. The inner edge of the plate e abuts against the longitudinal shoulder f' which is formed upon the plate d by the provision of the horizontal flange or extension F thereon. When the fish-plates 6 are properly arranged upon opposite sides of the rail sections and their oppositely extending horizontal plates d and e are disposed beneath the rail base and interlocked by the seating of the bosses g in the recesses f, it will be readily seen that any relative transverse movement of these fish-plates or joint sections beneath the base of the rail is effectually prevented.

45 In order to relieve the interlocking bosses g of undue strain, the fish-plates 5 and 6 are provided in their web engaging portions with the bolt receiving openings c, the openings in the plate 6 being threaded, as shown, for engagement by the threads on the ends of the connecting bolts h, said bolts also preventing any longitudinal movement of the joint members. It is, of course, understood that the webs of the rail sections are also provided with openings which register with the openings c and through which the fastening bolts are adapted to be disposed.

50 In Fig. 5 of the drawings I have illustrated a slightly modified form of the invention wherein the fish-plate 6' is provided with a stud i in its vertical portion to be received in an opening in the web of the rail so as to effectually overcome any tendency of the fish-plates or joint members to move longitudinally upon the rail.

From the foregoing it is thought that the construction and operation of my improved rail joint will be fully understood. The device is simple, and may be readily arranged 5 in position upon the rail sections at their abutting ends. The joint also provides an effectual reinforcing means or support for the rail at the joint thereof and is extremely substantial and rigid when applied to the 10 rail. The device may also be produced at a comparatively small cost.

While I have shown and described the 15 preferred construction and arrangement of the various parts, it will be understood that the device is susceptible of considerable modification without departing from the essential feature or sacrificing any of the advantages thereof.

Having thus described the invention what 20 is claimed is:—

1. A rail joint comprising two members adapted to be arranged upon opposite sides of the rail and having vertical portions engaging the web of the rail and laterally extending base engaging flanges on the lower edges of said vertical portions, horizontally disposed reversely extending plates formed on the outer edges of said base engaging portions to extend beneath the rail base, one of said plates having a longitudinally extending reduced portion provided in its 25 upper surface with a plurality of spaced depressions, said depressions being spaced from the longitudinal edge of the plate, the 30 plate of the other of said members being disposed between the rail base and said re-

duced portion of the first named plate and provided with a plurality of rectangular bosses on its under face to fit into said depressions whereby said plates are interlocked and held against relative transverse and longitudinal movement. 40

2. A rail joint comprising two members adapted to be arranged upon opposite sides of the rail and having vertical portions engaging with the web thereof, said members being also formed at the lower end of said vertical portions with lateral flanges to engage upon the rail base and reversely extending horizontally disposed plates to extend beneath the rail base, one of said plates being reduced in thickness at its inner edge and provided with a plurality of rectangular depressions in its upper surface, the other of said plates being disposed between 50 the rail base and said reduced portion of the rail base and provided with a plurality of rectangular bosses upon its under surface to be received in said depressions, whereby said plates are interlocked and 55 their relative transverse movement prevented, and bolts disposed through the vertical portions of said members and the web of the rail to prevent longitudinal movement of said members. 60

In testimony whereof I hereunto affix my signature in the presence of two witnesses.

JAMES HOWELL RAMSDELL.
